(57) **CLAIM**

The ornamental design for a sealing liner, as shown and described.

DESCRIPTION

FIG. 1 is a perspective view of a sealing liner showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is another perspective view thereof; and,

FIG. 9 is an enlarged view taken from section 9 of FIG. 4. In FIGS. 4 and 9, the broken line represents a sectional designation that forms no part of the claim.
